UNITED STATES PATENT OFFICE

RAYMOND J. HARRIS, OF WASHINGTON, DISTRICT OF COLUMBIA.

FLY CATCHER

Application filed January 10, 1928. Serial No. 245,653.

This invention relates to a fly catcher and it consists in the novel features hereinafter described and claimed.

ber until such time as they are incapacitated from flying or dead.

In the accompanying drawing:—

Figure 1 is a top plan view of the fly catcher;

Figure 2 is a side elevational view thereof; Figure 3 is a transverse sectional view thereof cut on the line 3—3 of Figure 1 and showing the parts in position when the device is used for catching flies;

Figure 4 is a similar view showing the position of the parts after the impounding chamber has been returned to dump the flies:

Figure 5 is a fragmentary detailed sectional view of the impounding chamber cut across a corner portion thereof. 65

The fly catcher comprises a handle member 1 formed from wire and which is bent upon itself at a point approximately midway between its ends and brought together at 2 and secured in any suitable manner to form a shank. From the said shank portion the opposite sides of the wire are extended outwardly as at 3 and then forwardly as at 4, the said forwardly extending portions 4 being provided at their extremities with return bends or hooks 5. 70 75

The fly catcher also includes an impounding chamber having side walls 6 and end walls 7. The rear edges of the end walls 7 are peaked as at 8 and a wire screen 9 is disposed over the rear edges of the side walls 6 and the end walls 7 and secured to the said walls in any suitable manner whereby the screen is substantially in the form of a trough having angularly disposed side portions, as best shown in Figures 3 and 4 of the drawing. The forward side of the impounding chamber is open and inclined panels 10 and 11 are disposed within the chamber and converge toward each other from the opposite edges of the open side of the chamber. The panel 11 is broader transversely than the panel 10. A door panel 12 is hingedly connected by means of a flexible strip 13 or its equivalent with the narrower panel 10 and the free edge portion of the door panel 12 is adapted to rest against the inner edge of the broader panel 11 when the parts are in the position as shown in Figure 3 of the drawing. The broader

panel 11 is less in length than the length of the impounding chamber so that ample clearance space is provided to permit the door panel 12 to swing freely without binding against the inner surfaces of the end walls 5 of the said chamber. The hooks 5 engage the edges of the panels 11 and hold them locked in position.

The end panels 7 are provided with slots 10 14 through which the portions 4 of the handle member 1 are passed and the hooks 5 are received in the slots 14 at one end of the impounding chamber. The inner surfaces of the panels 10 and 11 rest directly against the sides of the portions 4 of the handle member 1 and the edges of the panels 10 and 11 at one end thereof are caught under the hooks 5 as best shown in Figure 5 of the drawing, and thus the panels 10 and 11 are retained in proper position with relation to each other and the portions 4 of the handle member brace the inner portions of the said panels and the panels hold the handle member against longitudinal movement with relation to the impounding chamber.

When the device is used for catching flies, whether they be in the air or upon surfaces, the parts are in the position as shown in Figure 3 of the drawing. The handle member is 30 grasped and a stroke is made which carries the impounding chamber toward the fly or flies. The volume of air which surrounds the fly or flies passes between the panels 10 and 11 and strikes the door panel 12 and serves to 35 swing the same to an open position. At the same time, the centrifugal force incident to the movement of the impounding chamber further assists in swinging the door. Thus the volume of air which surrounds the fly or flies passes between the panels 10 and 11 and under the lower edge of the door and enters the impounding chamber. The fly or flies are carried with the said volume of air and enter the impounding chamber. The 40 fly or flies will strike against the screen 9 while the volume of air passes through the interstices or openings of the screen. When the forward movement of the impounding chamber is stopped, the door panel 12 falls by gravity and the fly or flies are trapped within the 45 impounding chamber. The movement of the closing of the door is speeded by the impetus or momentum imparted to the free edge thereof of when the impounding chamber comes to a 50 state of rest so that the door closes promptly as hereinbefore stated.

After the flies have been caught in the trap they may be killed by exposing them to heat. This may be done by presenting the impounding chamber to a flame or by placing the same 55 at an exposed position in the sun.

After the flies are dead and when it is desired to dump them from the impounding chamber the handle member 1 is used for 60 turning the impounding chamber so that the

parts assume the position as shown in Figure 4 of the drawing. Thus the flies will fall over the upper portion of the impounding chamber upon the outer surface of the door panel 12 which will then serve as a chute and direct 70 the flies out of the impounding chamber over the surface of the panel 10.

From the foregoing description taken in conjunction with the accompanying drawing, it will be seen that a fly catcher of simple and 75 durable structure is provided, that the same may be economically manufactured and the parts assembled and that the parts mutually co-operate with each other to strengthen the structure and to maintain themselves in proper 80 relation with respect to each other.

It is to be understood that the catcher may be used to advantage for catching all manner of insects that fly in the air, as for instance, mosquitoes, bees, or similar flying insects.

Having described the invention what is claimed is:—

1. An insect catcher comprising an impounding chamber open at opposite sides, a screen disposed over one side, inclined panels located in the chamber and extending from the edges of the sides, a door panel hingedly connected with one of the inclined panels, and a handle member having spaced branches 90 passing through the ends of the impounding chamber and having locking hooks engaging the edges of the inclined panels.

2. An insect catcher comprising an impounding chamber open at opposite sides, a screen disposed over one side, inclined panels located within the chamber and extending from the edges of the opposite sides, one of the panels being broader transversely than the other, a door panel hingedly connected 100 with the narrower panel and adapted to have its free edge engage the edge of the broader panel, and a handle having spaced end portions passing through the ends of the impounding chamber and disposed along the inclined panels and having locking hooks 105 engaged around the edges of the inclined panels.

3. An insect catcher comprising an impounding chamber open at opposite sides, a screen disposed over one side, inclined panels 115 located in the chamber and extending from the edges of the opposite side, a door panel hingedly connected with one of the inclined panels and adapted to engage the edge of the other inclined panel, a handle member provided with spaced end portions, said end portions passing through the end walls of the impounding chamber, and having means for locking engagement with the inclined panels.

4. An insect catcher comprising an impounding chamber open at opposite sides, said chamber having end walls provided with edges having angularly disposed portions, a screen disposed over the angularly disposed edge portions of the end walls, inclined panels 125

located interiorly of the impounding chamber and extending from the edges of the opposite side thereof, a door panel hingedly connected with one of the inclined panels and adapted to engage the other inclined panel, and a handle member having spaced end portions passing through the end walls of the impounding chamber and extending along the sides of the inclined panels, said end portions of the handle member being provided at their extremities with locking hooks engaging around the end portions of the inclined panels.

In testimony whereof I affix my signature.

RAYMOND J. HARRIS.
